PROCESS FOR THE DEHYDROGENATION OF
HYDROCARBONS

Walter A. Schulze and John C. Hillyer, Bartlesville, Okla., assignors to Phillips Petroleum Company, a corporation of Delaware

Application May 6, 1943, Serial No. 485,908

12 Claims. (Cl. 260—680)

This invention relates to a process for the production of diolefins of four and five carbon atoms per molecule from the corresponding paraffins. More particularly it relates to an improved process for dehydrogenation of a paraffin having four to five carbon atoms in successive dehydrogenation steps to produce the corresponding olefins and diolefins.

This invention is particularly applicable to the production of butadiene by the two-stage dehydrogenation of butane, i. e. dehydrogenation of butane to butenes in a first dehydrogenation step and dehydrogenation of a butene to butadiene in a second dehydrogenation step.

This is a continuation-in-part of the copending application Serial No. 358,008 filed September 23, 1940, now Patent No. 2,362,218, issued November 7, 1944, disclosing a process in which butene-2 obtained from the catalytic dehydrogenation of normal butane is separated and subsequently dehydrogenated to produce butadiene. The present invention is directly concerned with the recovery of butene-2 from both stages of dehydrogenation and particularly with the catalytic isomerization of butene-1 concurrently formed to promote the efficiency of product segregation from both of said stages of dehydrogenation.

An object of this invention is to provide an improved process for the production of a diolefin from the corresponding paraffin.

Another object of this invention is to provide such a process which is particularly applicable to the production of butadiene from butane.

Still another object of this invention is to provide an improved process for the production of butadiene from butane in which the butene-1, formed concurrently with the formation of butene-2, is converted to butene-2.

A further object of this invention is to provide an improved method for the separation of butene-2 and butadiene from the products of the catalytic dehydrogenation of C₄ hydrocarbons.

A particular advantage of the process of the present invention is that it provides for the extraction of butadiene and butene-2 from the effluents of both dehydrogenation steps in a single operation.

Other objects and advantages of the invention will be apparent to those skilled in the art from a consideration of the following detailed disclosure and the accompanying drawings.

Figure 1 of the drawings is a diagrammatic elevational view of an arrangement of apparatus suitable for carrying out the present invention.

Figure 2 is a diagrammatic elevational view of

another arrangement of apparatus for carrying out the process of this invention.

It has been proposed to produce butadiene by the catalytic dehydrogenation of normal C₄ paraffins, olefins, and mixtures thereof, with various methods being suggested to enable the provision of suitable butylene concentrations in the dehydrogenation feed stocks. Such methods have included the dehydrogenation of normal butane to yield paraffin-olefin mixtures, and the treatment of said mixtures in the same or different dehydrogenation steps to further convert the olefins to the diolefins. Other methods have indicated improved efficiency and economy from the segregation of normal butylenes from unconverted paraffins prior to conversion to produce the diolefin. The latter methods have been preferred generally for the reason that the optimum dehydrogenation conditions for the paraffin-olefin and the olefin-diolefin conversions are distinctly different, and overall process yields and economics have favored the relatively complete segregation of butylenes as the feed stock to the olefin-diolefin conversion step.

Heretofore, means for accomplishing butylene segregation or purification from n-butane have been handicapped by the physical properties of the two isomers, butene-1 and butene-2 produced in the dehydrogenation reactions. Furthermore, these properties, and particularly those of butene-1, have complicated the separation and recovery of butadiene as the end product of the manufacturing process.

In our copending application, Serial No. 358,008, referred to above, we have disclosed an improved method for producing butene-2 as the feed stock to a second dehydrogenation step by means of catalytic isomerization of butene-1 to butene-2. However, in said second step, the re-establishment of the equilibrium between the normal butylene isomers at the temperature level of the dehydrogenation with formation of increased amounts of butene-1 has resulted in increased difficulty in butadiene separation and purification, and also in the presence of considerable amounts of butene-1 in butylene mixtures recycled to the said second dehydrogenation step.

We have now discovered a process whereby both butadiene purification and butylene segregation steps are accomplished more efficiently and the butylene feed to the second dehydrogenation stage comprises essentially butene-2. This last-named improvement has been found to result in improved butadiene yields due apparently to the more sat-

isfactory characteristics of butene-2 as feed to the olefin-diolefin conversion step.

It is an additional feature of our new process that the basic operations are cooperative to an unusual degree, and may, if desired, be carried out in units of process equipment serving both stages of dehydrogenation. This advantage may be utilized to reduce the equipment requirements and operating costs for butadiene production at the same that improved yields are obtained as a result of the present invention.

In one specific embodiment, our process comprises the following steps: (1) normal butane is catalytically dehydrogenated in a first dehydrogenation stage to produce normal butylenes; (2) the butane-butylenes condensate from step 1 is catalytically isomerized to convert butene-1 to butene-2; (3) the effluent from the isomerization treatment is treated by solvent extraction or fractionation to separate butene-2 from the other C₄ components which include unconverted n-butane to be recycled to the first dehydrogenation stage; (4) the butene-2 is catalytically dehydrogenated in a second stage to produce butadiene; (5) the C₄ condensate from step 4 is treated with a selective solvent to separate butadiene and butene-2 from butene-1 and butane; (6) the butadiene-butene-2 mixture is fractionated to separate substantially pure butadiene from butene-2; (7) the butane-butene-1 stream is passed to the isomerization unit and the butene-2 produced is recovered with that derived from the first stage dehydrogenation.

In addition to these basic operations, several other auxiliary steps may be desirable in some circumstances. These may include a further fractionation of the n-butane-butene-1 mixture being recycled to the first stage of dehydrogenation to recover and isomerize further quantities of butene-1, or the treatment of the recycle streams to either dehydrogenation stage to remove small amounts of higher boiling liquid and/or isobutylene from the system.

With reference to Figure 1 of the drawings, the feed, in this instance n-butane, is passed through line 1 to the first stage of the dehydrogenation, designated by the numeral 2, where the feed is raised to the reaction temperature and passed into contact with a catalyst under conditions capable of effecting dehydrogenation of n-butane to butenes. The effluent of the first stage of the dehydrogenation comprises unconverted butane and normal butylenes, butene-1 and the 2-butenes, together with C₃ and lighter hydrocarbons, C₅ and heavier hydrocarbons, and some isobutylene. The effluent of the dehydrogenation is cooled, as by the cooler 3, and passed to a separation step, designated by the numeral 4, wherein the effluent is subjected to compression and cooling to form condensate while at the same time the C₃ and heavier hydrocarbons and the C₅ and lighter hydrocarbons are separated from the C₄ hydrocarbons. The C₄ hydrocarbon stream, which may advantageously contain a part of the C₃ and/or lighter hydrocarbons is passed to the isomerization step 5 where conversion of butene-1 present in the stream to the butene-2 isomers is effected in the presence of a suitable catalyst. The effluent from unit 5 passes to absorber 7 where a selective solvent is utilized to absorb the butene-2, while a stream of predominantly n-butane with a greatly reduced butene-1 content passes through line 8 to be recycled to the first stage dehydrogenation. Optionally, treatment to separate relatively small amounts of butene-1 re-

maining in the n-butane recycle stream may be carried out in unit 9. This unit may be a simple fractionating column with the butylenes taken overhead and returned through line 30 to either the isomerization unit 5 or the isobutylene removal unit 29. The n-butane from fractionator 9 is then recycled through line 10 to the first stage dehydrogenation.

10 The butene-2 is stripped from the solvent in stripper 11 and passes through line 12 to be utilized as feed to the second stage dehydrogenation. When this butene-2 concentrate contains sufficient butadiene formed in the first stage dehydrogenation, it may be desirable to pass the stream from line 12 through line 28 to column 23 in order to recover this butadiene.

15 A feed stream comprising fresh and recycle butene-2 is catalytically dehydrogenated in unit 13 under conditions selected to effect partial conversion to butadiene, and the dehydrogenation products are cooled, compressed, and treated in units 14 and 15 to collect a C₄ condensate comprising butadiene and butylenes.

20 The second stage C₄ condensate then passes to column 16 in which a partial removal of butene-2 along with traces of heavier liquid is carried out. The overhead product from this fractionation passes through line 17 to absorber 18, while the bottoms fraction is taken through line 19 to a subsequent depentanizing or stripping operation in column 25.

25 The absorber 18 operates with a selective solvent for butene-2 and butadiene, and these components are separated from the stream entering by line 17. The unabsorbed portion comprising butene-1 and smaller quantities of isobutylene and n-butane formed over the second stage catalyst passes out through line 20. Some butene-2 may also pass through and be recovered in subsequent processing. When isobutylene removal is practised, the stream may pass through removal unit 29 for selective polymerization treatment or the like. This location for the isobutylene removal unit is preferred, since maximum isobutylene concentrations are present in the stream passing through line 20.

30 The butene-2 and butadiene are stripped from the solvent in stripper 21 and pass through line 22 to butadiene column 23. In this column substantially pure butadiene is taken overhead through line 24 to storage, while butene-2 is removed as the bottoms product through line 19 to column 25. This column 25 may be used to fractionate the total recycle butene-2 from the bottoms of columns 16 and 23, with recycle butene-2 taken overhead through lines 26 and 12 to the second stage dehydrogenation unit. Alternately, the butene-2 from the bottom of column 23 may be recycled directly through lines 27 and 12.

35 In Figure 2 a variation in the sequence of the same basic process steps is shown whereby a single solvent absorption unit is utilized to treat the C₄ condensate from both stages of dehydrogenation. In this arrangement, the products of normal butane dehydrogenation in unit 2 are treated to recover a predominantly C₄ condensate comprising butane and mixed butylenes in unit 4. This condensate passes to isomerization unit 5 where butene-1 is converted to butene-2. The effluent comprising normal butane, butene-2 and any unconverted butene-1 then passes to absorber 7 for selective absorption of the butene-2 and any butadiene formed in the first stage.

40 The second dehydrogenation stage operating on a predominantly butene-2 feed obtained as de-

scribed hereinafter is indicated by unit 13. A C₄ condensate comprising normal butylenes and butadiene is collected in unit 15. This condensate passes to fractionator 16 where partial removal of butene-2 along with traces of higher boiling liquid is accomplished. The overhead product from column 16 passes through line 32 to absorber 7 for selective absorption of butadiene and the remaining butene-2.

The unabsorbed hydrocarbons from absorber 7 comprise n-butane and butene-1 from both the first and second stages of dehydrogenation. This mixture passes through line 8 to column 9 which is operated to produce a bottoms product of substantially olefin-free n-butane removed through line 10 as recycle stock for the first stage dehydrogenation. The overhead fraction taken through line 30 contains butene-1 together with any isobutylene formed during dehydrogenation, and some n-butane may be included depending on the precision of the fractionation.

Said overhead fraction in line 30 is returned to isomerization unit 5 for further conversion of butene-1 to butene-2. The stream or a portion thereof may be passed intermittently or continuously to unit 29 for the removal of isobutylene by selective polymerization, or the like to prevent the building-up of isobutylene in the system. The butene-2 produced by isomerization of recycled butene-1 is thus combined with that recovered from the two dehydrogenation operations, and the amount of butene-1 separated in column 9 is controlled by the completeness of conversion in unit 5.

The rich solvent from absorber 7 is stripped in stripper 11 to remove butene-2 and butadiene. This mixture then passes to butadiene column 23 which operates to separate substantially pure butadiene as the overhead product. The butadiene is removed through line 24 to storage, while the butene-2 bottoms fraction is taken through line 12 and combined with the butene-2 from column 25 as feed to the second dehydrogenation stage. This last-named column 25 serves to strip butene-2 from higher boiling liquids in the bottoms fraction from column 16. If necessary, the entire butene-2 stream may be similarly treated in column 25.

Other possible alternatives are illustrated in Figure 2 for application in special circumstances. Thus, in some cases depending on the butadiene concentration in the stream and the particular isomerization catalyst, it may be desirable to pass the butadiene-butylene mixture from fractionator 16 to the isomerization unit 5. This flow enables the isomerization of butene-1 in the second stage effluent prior to treatment with the selective solvent and may eliminate the use of column 9 for separating olefin from the n-butane recycle stream to the first dehydrogenation stage. However, in many instances, unless the isomerization catalyst is carefully chosen, the instability of the diolefin favors butadiene removal prior to isomerization.

Further, the first stage condensate may be passed directly to the absorption unit through lines 32 and 34 for absorption of butene-2 prior to isomerization of butene-1. This arrangement favors the isomerization reaction by lowering the butene-2 concentration in the feed to unit 5 and may be employed when suitable absorption and fractionation capacity are available to obtain clean separation of the somewhat greater quantities of butene-1 from butene-2 and later from n-butane.

The flow diagrams thus illustrated and described feature the use of catalytic isomerization to reduce fractionation requirements for butene-1 separation and are particularly adapted to the utilization of solvents exhibiting relatively greater solubility for 2-olefins than for 1-olefin. In the manner indicated, the sequence of isomerization and solvent extraction operations cooperatively convert the butene-1 to butene-2 and assist in the substantially complete recovery of both butene-2 and butadiene and in the segregation of unconverted n-butane for return to the first dehydrogenation stage. Other modifications may be devised in view of the disclosed principles, 15 without departing from the teachings of this invention.

In the first dehydrogenation stage producing normal butylenes, the preferred procedure is the treatment of normal butane over a dehydrogenating catalyst under conditions which result in the conversion of a substantial proportion of the butane to the corresponding olefins. Other sources of butylenes may of course be utilized if available, although preliminary purification steps, 20 e. g. isobutylene separation, may be required.

The dehydrogenation catalysts and conditions for the paraffin-olefin conversion are chosen to yield adequate amounts of olefins at reasonable per pass conversion in order to maintain high selectivity in butylene production. While a great many dehydrogenation catalysts may be used, it is usually preferred to employ solid contact catalysts comprising bauxite, synthetic aluminas or magnesia, often bearing or promoted with metal oxides including those of chromium, nickel, zirconium, tungsten, zinc, iron, and copper.

The conditions of temperature, pressure, flow rate, etc., used in the paraffin-olefin conversion will depend largely on the activity of the catalyst and its range of maximum efficiency. The charge vapors may, for example, be treated at temperatures of about 900 to about 1200° F. and near-atmospheric pressures, to obtain adequate conversion to butylenes. The vapors may be subjected to two or more successive treatments in a series of catalyst chambers or sections containing catalyst of the same or gradually increasing activity, or any portion of the vapors may be recycled with fresh feed to the catalyst. These and other known operating devices may be utilized to attain the desired conversion of the normal butane feed.

The dehydrogenation products are handled in conventional equipment to segregate the components used in subsequent process steps. The customary methods of cooling, compressing, and fractionally condensing or absorbing C₄ hydrocarbons are suitable and may include one or more stages of compression followed by an oil absorption step or its equivalent to absorb C₄ hydrocarbons from the C₃ and lower boiling hydrocarbons and fixed gases. The condensate later stripped from the absorption oil may contain minor amounts of C₃ hydrocarbons which may be removed at any suitable point in the processing steps.

For the isomerization of butene-1 to butene-2, catalysts are chosen on the basis of their activity in the temperature range favorable to maximum butene-2 formation, and should not promote polymerization or other undesirable reactions which destroy or convert the butylenes to unusable form. Since the equilibrium between butene-1 and butene-2 favors maximum butene-2 concentration at low temperatures, catalysts ac-

tive in the range of about 200 to about 600° F. are preferred.

Among the catalysts which have been found suitable for the isomerization are several of an acidic nature. These include mineral materials containing acidic substances such as certain clays and silicates, salts such as aluminum phosphate and the like, or strong mineral acids in suitable concentration and often supported on adsorbent carriers. In employing catalysts of this type, precautions are observed to avoid undesired polymerization, as by regulation of the water content of the catalyst and/or of the hydrocarbons.

Other types of catalysts which are active and often preferred are those comprising magnesia in natural or synthetic form. These catalysts have the peculiar property of being highly active in substantially anhydrous state, so that the feed, the catalyst mass, and the treating conditions are regulated to produce and maintain substantially anhydrous conditions. Further catalysts such as brucite after activating treatment to remove water and adsorbed gases, as described in the copending application of Drennan, Serial No. 446,771, filed June 12, 1942, are sufficiently active at temperatures in the range of about 100 to about 400° F. to enable substantially equilibrium isomerization at said temperatures. The resulting butene-2 concentrations may amount to about 80-90 per cent or more of the total normal butylenes in the feed to the isomerization unit. Said catalysts are further characterized by low activity toward polymerization, and may be employed, if desired, to treat hydrocarbon mixtures containing relatively large concentrations of butadiene and/or isobutylene without losses of said components.

The operation of the isomerization unit involves conventional equipment, and may consist of passage of the hydrocarbon fluid at suitable flow rates over a bed or through a body of catalyst. The feed is ordinarily preheated to operating temperature and may be substantially dehydrated when employing a catalyst most highly active in anhydrous state. Liquid phase contacting at relatively low flow rates is often preferred, and suitable pressures may be utilized to prevent vaporization. In other instances, vapor phase contacting may be utilized at lower pressures and/or higher temperatures.

The effluent from the isomerization catalyst usually contains large proportions of unconverted normal butane which must be separated from the unsaturated components for recycle to the first stage dehydrogenation. In many cases, when butylene production is the principal object, it will be desirable to limit the olefin content of this butane recycle stream in order to prolong catalyst life and improve the reaction efficiency. In case of restrictions on the olefin content of the butane recycled, and in view of the benefits of relatively complete butene-2 recovery, an absorption operation utilizing a selective solvent is often preferred to separate butene-2 as charge to the second dehydrogenation stage.

However, when the first stage condensate is treated over a highly efficient isomerization catalyst, the unconverted butene-1 concentration may be reduced so low that the butane and lighter fraction separated from butene-2 by fractionation may be recycled satisfactorily to the first stage dehydrogenation.

The use of certain selective solvents for the present process is particularly advantageous because the solvents while exhibiting suitable pref-

erential solubility for unsaturates as compared to paraffins, are also found to exhibit preferential solubility for 2-olefins as compared to 1-olefin. Therefore, in the use of these solvents, operating conditions such as the solvent-hydrocarbon ratio, etc., may be regulated to achieve complete absorption of butene-2 while butene-1 is substantially unabsorbed and passes out with the paraffins. Thus, when the butene-1 concentration is sufficiently reduced by the isomerization treatment, the raffinate from the absorber may be recycled to the first dehydrogenation stage with no further treatment for olefin separation. In other cases, supplemental butene-1 separation and/or isobutylene removal may be desirable.

In the second dehydrogenation stage, the conversion of butene-2 to butadiene is usually carried out at temperatures of about 1100 to about 1300° F., near-atmospheric pressures, and with butene partial pressures in the charge vapors below one atmosphere. A convenient method of operation with reduced butene partial pressures involves the use of an inert diluent, preferably steam, with the butene-2 charge to regulate the butene partial pressure and space velocity in the catalyst zone.

Catalysts for the second stage dehydrogenation are in general less active than those employed in the first stage and may be pretreated and/or compounded with various materials to impart resistance to poisoning by water vapor and to suppress polymerization and cracking reactions at the high temperatures employed. Suitable catalysts include bauxite, brucite, synthetic alumina and/or magnesia-alumina combinations, and composite or impregnated catalysts prepared from bauxite, alumina or magnesia carriers bearing minor amounts of barium or strontium hydroxides.

The second stage dehydrogenation may be conducted to obtain the maximum butene conversion compatible with high selectivity in butadiene formation. The dehydrogenation products are cooled, compressed and treated to separate a predominantly C₄ condensate from lighter products. This condensate containing butadiene, unconverted butene-2, butene-1, and isobutylene formed by isomerization of the butene-2 charge, and traces of butane produced over the catalyst may be first fractionated to separate some of the butene-2 and heavier material to facilitate the solvent absorption step.

The course of the absorption operation is substantially the same as that described for the first stage condensate, with butadiene absorbed along with butene-2. Complete separation of butane is essential to the recovery of high purity butadiene. The butene-1 and n-butane when processed over the isomerization catalyst are handled in the same fashion as the components of the first stage condensate. Isobutylene removal may be practised at any point subsequent to the solvent absorption step, and is preferably carried out at the stage where the isobutylene concentration reaches a maximum.

The butadiene-butene-2 extract recovered from the solvent is separated into its components by precise fractionation, yielding substantially pure butadiene and butene-2 for recycling to the second stage catalyst after combination with the other butene-2 streams from other parts of the system.

This method of supplying butene-2 as feed to the dehydrogenation operation producing butadiene enables a more selective conversion even

under more severe conditions than when a mixed butylene feed or butene-1 alone is employed. This is apparently due to the greater stability of the carbon skeleton of butene-2 as compared to butene-1 and to the consequent higher ultimate yields of butadiene and decreased losses of butylene feed in the form of light gases and carbon. Thus, the present process makes possible higher per pass conversions and/or higher butadiene yields from equivalent amounts of butylene feed stocks by virtue of the isomerization of butene-1 and the selective recovery of butene-2.

In view of the above-described operations and the advantages obtained, the benefits of the present process will be obvious. The sequence of the various steps and the selection of operational schemes such as are illustrated in the flow diagrams will depend on process economics for each individual plant. Some further illustration of the principles and operations of the process may, however, be provided in the following exemplary operation, substantially as shown in Figure 1.

Normal butane may be dehydrogenated over alumina-chromium oxide type catalyst to convert 30-40 per cent of the charge per pass with high selectivity in normal butylene formation. The products from this treatment after separation of most of the C₃ and lighter hydrocarbons may be collected as a C₄ condensate with the following typical composition:

	Mol per cent
C ₃ and lighter	2-3
Butene-1	12-13
Butene-2	23-24
n-Butane	61-62

After substantially complete dehydration, isomerization of this condensate over activated brucite catalyst at temperatures of 250-300° F. produces a composition as follows:

	Mol per cent
C ₃ and lighter	2-3
Butene-1	2-3
Butene-2	33-34
n-Butane	61-62

When the isomerized condensate is contacted in a liquid-liquid absorption operation with furfural as the selective solvent, the following separation of raffinate from extract is accomplished:

	Raffinate, mol per cent	Extract, mol per cent
C ₃ and lighter	3-4	1-2
Butene-1	3-4	1-2
Butene-2	95-96	1-2
n-Butane	92-93	2-3

The raffinate may be recycled directly to the n-butane dehydrogenation step while the butene-2 is used as a portion of the feed to the second stage of dehydrogenation.

The butene-2 may be diluted with steam to produce a charge mixture with a steam-butene molar ratio of three or somewhat higher and dehydrogenated over bauxite bearing barium hydroxide at 1200° F. to convert 30-40 per cent of the butene-2 per pass. The C₄ condensate recovered from the dehydrogenation products will have the following approximate composition:

	Mol per cent
C ₃ and lighter	7.5
Butadiene	16-17
Butylenes	72-73
Butane	3
C ₅ ⁺	0.5

After a preliminary fractionation to remove a portion of the butene-2 and heavier material, the condensate is contacted with furfural in an absorption step, and the raffinate and extract show the following separation:

	Raffinate, mol per cent	Extract, mol per cent
C ₃ and lighter	16	68-70
Butadiene	7	-----
Isobutylene	50-60	-----
Butene-1	10-20	30-32
Butene-2	5-6	-----
Butane	-----	-----

Fractionation of the extract produces butadiene of 97-99 per cent purity. The butene-2 also produced is combined with that recovered by stripping C₅ and heavier from the preliminary condensate fractionation and that produced from the first stage condensate to give a feed stock containing over 95 mol per cent of butene-2.

The raffinate is depropanized to continuously separate and vent a substantial portion of the C₃ and lighter material, and treated over a selective polymerization catalyst to effect isobutylene removal. The adjunct of the polymerization step is a fractionation operation which separates C₃ and heavier liquid from the C₄ raffinate.

When added to the first stage condensate ahead of the isomerization unit, the composition of the combined stream is approximately as follows:

	Mol per cent
C ₃ and lighter	2
Isobutylene	2
Butene-1	35-40
Butene-2	5-10
n-Butane	51

This feed to the isomerization step undergoes substantially the same extent of butene-1 conversion as indicated above for the first stage condensate.

When the butylene content of the raffinate from the first stage absorber exceeds about 3-4 mol per cent, a simple topping operation may be employed with recycle of the butene-1 thus separated to the isomerization unit, preferably by addition ahead of the depropanizer of the isobutylene removal unit.

When the above described operation is altered to incorporate the flow of Figure 2, the composition of product streams is not greatly changed. The principal variation is the increased fractionation load for unit 9 separating butene-1 from n-butane with greater precision.

From the foregoing, it will be apparent that the isomerization of butene-1 to butene-2 at the indicated points in the two-stage dehydrogenation system enables the more efficient and economical operation of the butylene segregation and butadiene purification steps. Of particular importance are the reduction in the number and size of precise fractionating units which are otherwise required for butene-1 separation, and the added benefits of charging substantially only butene-2 to the second stage dehydrogenation.

In case the butylenes for the olefin-diolefin conversion are available from a source other than n-butane dehydrogenation, the process of this invention is applicable to the treatment of any butane-butylene mixture with, perhaps, suitable revisions for handling larger quantities of isobutylene and different disposal of the paraffins discarded from the system. Such revisions may include the use of a single catalyst and/or reagent

to effect isobutylene removal and butene-1 isomerization as described in our copending application Serial No. 369,490, filed December 10, 1940.

For the purpose of facilitating the description of the process, the treatment of the C₄ hydrocarbons has been discussed in connection with the drawings. We have found that the same procedure may be followed in the treatment of C₅ hydrocarbons for the production of pentadienes. Normal pentane may be dehydrogenated in a first step forming normal pentenes including pentene-1 and 2-pentenes, the pentene-1 isomerized to 2-pentenes, and the pentene-2 separated for dehydrogenation in a second step to produce pentadiene. The pentene-1 formed in the second dehydrogenation may be separated from the effluent and passed to the isomerization step. The various streams may be handled in the same manner as the C₄ streams, hereinafter more fully discussed in detail, and this application of the invention will be evident to those skilled in the art.

These and other modifications and extensions of the present invention will be obvious in the light of the disclosure and specific descriptions provided. Therefore no limitations are implied except as defined in the following claims.

We claim:

1. The process for the production of a diolefin of four to five carbon atoms per molecule from the corresponding normal paraffin which comprises catalytically dehydrogenating said paraffin under conditions effecting conversion of a substantial portion of the normal paraffin to the corresponding olefins including the 1-olefin and 2-olefins; catalytically isomerizing the olefins in the effluent of the dehydrogenation step under conditions effecting conversion of at least a portion of said 1-olefin to 2-olefins as the principal reaction; separating the 2-olefins from the 1-olefin and unconverted paraffin in the effluent of said isomerization; recycling the unconverted paraffin to said dehydrogenation; catalytically dehydrogenating said 2-olefins under conditions effecting conversion of a substantial portion of said 2-olefins to the corresponding diolefin with the simultaneous formation of some of the 1-olefin; separating the diolefin and unconverted 2-olefin in admixture from the 1-olefin in the effluent of said olefin dehydrogenation step, treating the mixture of diolefin and unconverted 2-olefin to separate same into a fraction of substantially pure diolefin and a fraction of the unconverted 2-olefin, and recycling the unconverted 2-olefins to the olefin dehydrogenation step.

2. The process for the production of a diolefin of 4 to 5 carbon atoms per molecule from the corresponding normal paraffin which comprises catalytically dehydrogenating said paraffin in a first dehydrogenation step forming the corresponding olefins comprising the 1-olefin and 2-olefins; catalytically isomerizing the olefins in the effluent of the dehydrogenation step under conditions effecting conversion of at least a portion of said 1-olefin to 2-olefins as the principal reaction; separating the 2-olefins in the effluent of the isomerization step from unconverted paraffin and unconverted 1-olefin; separating the paraffin from the 1-olefin; recycling the paraffin to the first dehydrogenation step; recycling the unconverted 1-olefin to the isomerization step; catalytically dehydrogenating said 2-olefins in a second dehydrogenation step forming the corresponding diolefin with the simultaneous formation of the 1-olefin; separating the diolefin and unconverted

2-olefins from the 1-olefin in the effluent of the second dehydrogenation step; passing the 1-olefin to the isomerization step; separating the diolefin in substantially pure form from the unconverted 2-olefins; and recycling the unconverted 2-olefin to the second dehydrogenation step.

3. The process for the production of a diolefin of four to five carbon atoms per molecule from the corresponding normal paraffin which comprises catalytically dehydrogenating said paraffin in a first dehydrogenation step, forming the corresponding olefins comprising the 1-olefin and 2-olefins with the simultaneous formation of the corresponding isoolefin and diolefin; catalytically isomerizing the olefins in the effluent of the dehydrogenation step under conditions effecting conversion of at least a portion of said 1-olefin to 2-olefins as the principal reaction; separating the 2-olefins and the diolefin in the effluent of the isomerization step from the unconverted normal paraffin, the isoolefin, and the unconverted 1-olefin; segregating the unconverted normal paraffin, the 1-olefin, and the isoolefin; recycling the unconverted normal paraffin to the first dehydrogenation step; recycling the unconverted 1-olefin to the isomerization step; withdrawing the isoolefin from the system; separating the diolefin from the 2-olefins in a second separation step; catalytically dehydrogenating said 2-olefins in a second dehydrogenation step forming the corresponding diolefin with the simultaneous formation of the 1-olefin and isoolefin; separating the diolefin and unconverted 2-olefins from the 1-olefin and isoolefin in the effluent of the second dehydrogenation step; separating the 1-olefin from the isoolefin; withdrawing the isoolefin from the system; passing the 1-olefin to the isomerization step; separating the diolefin in substantially pure form from the unconverted 2-olefins; and recycling the unconverted 2-olefins to the second dehydrogenation step.

4. The process for the production of pentadiene from normal pentane which comprises catalytically dehydrogenating normal pentane under conditions effecting conversion of a substantial portion of the normal pentane to the corresponding pentenes including pentene-1 and the 2-pentenes; catalytically isomerizing the olefins in the effluent of the dehydrogenation step under conditions effecting conversion of at least a portion of said pentene-1 to pentene-2 as the principal reaction, separating the pentene-2 from the pentene-1 and unconverted normal pentane in the effluent of said isomerization step, separating the pentene-1 from the unconverted normal pentane, passing the pentene-1 to the isomerization step, recycling the unconverted normal pentane to the dehydrogenation step, catalytically dehydrogenating the said pentene-2 under conditions effecting conversion of a substantial portion of said pentene-2 to pentadiene with the simultaneous formation of some pentene-1, separating pentadiene and unconverted pentene-2 from the pentene-1 in the effluent of said last-mentioned dehydrogenation step, separating substantially pure pentadiene from the unconverted pentene-2, recycling the unconverted pentene-2 to said last-mentioned dehydrogenation step, and passing the pentene-1 to the isomerization step.

5. The process for the production of butadiene from butane which comprises catalytically dehydrogenating normal butane under conditions effecting conversion of a substantial portion of the normal butane to the corresponding butenes including butene-1 and the 2-butenes, catalytically

cally isomerizing the olefins in the effluent of the dehydrogenation step under conditions effecting conversion of at least a portion of said butene-1 to butene-2 as the principal reaction, separating the butene-2 from the butene-1 and unconverted normal butane in the effluent of said isomerization step, separating the butene-1 from the unconverted normal butane, passing the butene-1 so separated to the isomerization step, recycling the unconverted normal butane to the dehydrogenation step, catalytically dehydrogenating the butene-2 under conditions effecting conversion of a substantial portion of said butene-2 to butadiene with the simultaneous formation of some butene-1, separating butadiene and unconverted butene-2 from the butene-1 in the effluent of said last-mentioned dehydrogenation step, separating substantially pure butadiene from the unconverted butene-2, recycling the unconverted butene-2 to said last-mentioned dehydrogenation step and passing the butene-1 to the isomerization step.

6. The process for the production of butadiene from normal butane which comprises catalytically dehydrogenating normal butane in a first dehydrogenation step forming butene-1 and 2-butenes with the simultaneous formation of butadiene; catalytically isomerizing the butenes in the effluent of the dehydrogenation step under conditions effecting conversion of at least a portion of said butene-1 to butene-2 as the principal reaction; separating butene-2 and butadiene in the effluent of the isomerization step from unconverted normal butane and unconverted butene-1; separating the unconverted normal butane from the butene-1; recycling the unconverted normal butane to the first dehydrogenation step; passing the butene-1 to the isomerization step; separating the butadiene from the butene-2; catalytically dehydrogenating the butene-2 in a second dehydrogenation step forming butadiene with the simultaneous formation of butene-1; separating the butadiene and unconverted butene-2 from the butene-1 in the effluent of the second dehydrogenation step; passing the butene-1 to the isomerization step; separating the butadiene from the unconverted butene-2; and recycling the unconverted butene-2 to the second dehydrogenation step.

7. The process for the production of butadiene from normal butane which comprises catalytically dehydrogenating normal butane in a first dehydrogenation step forming butene-1 and butene-2 with the simultaneous formation of butadiene; catalytically isomerizing the butenes in the effluent of dehydrogenating step under conditions effecting conversion of at least a portion of said butene-1 to 2-butenes as the principal reaction; separating the 2-butenes and butadiene in the effluent of the isomerization step from unconverted normal butane and unconverted butene-1; separating the normal butane from the butene-1; recycling the unconverted normal butane to the first dehydrogenation step; recycling the unconverted butene-1 to the isomerization step; separating the butadiene from the butene-2; catalytically dehydrogenating the butene-2 in a second dehydrogenation step forming butadiene with simultaneous formation of butene-1 and isobutene; separating the butadiene and unconverted butene-2 from the butene-1 and isobutene in the effluent of the second dehydrogenation step; separating the butene-1 from the isobutene; withdrawing the isobutene from the system; passing the butene-1 to the isomerization step; separating

the butadiene from the unconverted butene-2; and recycling the unconverted butene-2 to the second dehydrogenation step.

8. The process for the production of butadiene from normal butane which comprises catalytically dehydrogenating normal butane in a first dehydrogenation step, forming butene-1 and 2-butenes with the simultaneous formation of butadiene and isobutene; catalytically isomerizing the butenes in the effluent of the dehydrogenation step under conditions effecting conversion of at least a portion of said butene-1 to 2-butenes as the principal reaction; separating butene-2 and the butadiene in the effluent of the isomerization step from unconverted normal butane, isobutene, and unconverted butene-1; segregating the normal butane, isobutene, and the butene-1; recycling the unconverted normal butane to the first dehydrogenation step; recycling the unconverted butene-1 to the isomerization step; withdrawing the isobutene from the system; separating the butadiene from the butene-2; catalytically dehydrogenating the butene-2 in a second dehydrogenation step forming butadiene with the simultaneous formation of butene-1; separating the butadiene and the unconverted butene-2 from the butene-1 in the effluent of the second dehydrogenation step; passing the butene-1 to the isomerization step; separating the butadiene from the unconverted butene-2; and recycling the unconverted butene-2 to the second dehydrogenation step.

9. The process for the production of butadiene from normal butane which comprises catalytically dehydrogenating normal butane under conditions effecting conversion of a substantial portion of the normal butane to normal butenes including butene-1 and 2-butenes; catalytically isomerizing the butenes in the effluent of the dehydrogenation step under conditions effecting conversion of at least a portion of said butene-1 to 2-butenes as the principal reaction; contacting the effluent of said isomerization with a selective solvent effecting removal of butene-2 from the butene-1 and unconverted normal butane; recycling the unconverted normal butane to the said dehydrogenation; catalytically dehydrogenating the butene-2 under conditions effecting conversion of a substantial portion of said butene-2 to butadiene with the simultaneous formation of butene-1; contacting the effluent of said last-mentioned dehydrogenation with a selective solvent effecting removal of the butadiene and the butene-2 from the butene-1 therein; passing the butene-1 to the isomerization; separating butadiene from the unconverted butene-2; and recycling the unconverted butene-2 to said last-mentioned dehydrogenation.

10. The process for the production of butadiene from normal butane which comprises catalytically dehydrogenating normal butane under conditions effecting conversion of a substantial portion of the normal butane to the butenes including butene-1 and 2-butenes with the simultaneous formation of butadiene; catalytically isomerizing the butenes in the effluent of the dehydrogenation step under conditions effecting conversion of at least a portion of said butene-1 to 2-butenes as the principal reaction; contacting the effluent of said isomerization step with a selective solvent in a separation step effecting removal of the 2-butenes and the butadiene from the butene-1 and unconverted normal butane therein; recycling the unconverted normal butane

to said first dehydrogenation step; separating the butadiene from the butene-2; catalytically dehydrogenating the butene-2 under conditions effecting conversion of a substantial portion of said butene-2 to butadiene with the simultaneous formation of butene-1; separating at least a portion of the unconverted butene-2 from the butadiene and butene-1 in the effluent of the second dehydrogenation step; recycling the unconverted butene-2 to the second dehydrogenation step; and passing the butadiene and butene-1 to the first-mentioned separation step.

11. The process of producing butadiene from normal butane which comprises catalytically dehydrogenating normal butane to normal butenes including butene-1 and butene-2 in a first dehydrogenation stage, segregating a predominantly C₄ hydrocarbon fraction from the effluent, said fraction containing the butane and butene content of said effluent, passing said fraction through a catalytic isomerization step and thereby effecting isomerization of said butene-1 to butene-2 as substantially the sole reaction, extracting the isomerization effluent with a selective solvent having preferential solubility for butene-2 as compared to butene-1 and thereby effecting solution of the butene-2 content while allowing the normal butane and butene-1 content to pass through undissolved, recycling the undissolved normal butane to said dehydrogenation step, stripping the dissolved butene-2 from the rich solvent, catalytically dehydrogenating the stripped butene-2 to butadiene in a second dehydrogenation stage with the simultaneous formation of some butene-1, segregating a C₄ hydrocarbon fraction from the effluent, said fraction containing the butadiene and butene-1 content and at least a portion of the butene-2 content of said effluent, extracting said fraction with a selective solvent having preferential solubility for butene-2 as compared to butene-1 and thereby effecting solution of the butadiene and butene-2 content while allowing the butene-1 content to pass through undissolved, recycling the undissolved butene-1 to said isomerization step, stripping the dissolved butadiene and butene-2 from

5 the rich solvent, fractionally distilling the stripped butadiene and butene-2 to produce an overhead of substantially pure butadiene and a bottoms of butene-2, and recycling the butene-2 content of said bottoms to said second dehydrogenation step.

12. The process of producing butadiene from normal butane which comprises catalytically dehydrogenating normal butane to normal butenes including butene-1 and butene-2 in a first dehydrogenation stage, segregating a predominantly C₄ hydrocarbon fraction from the effluent, said fraction containing the butane and butene content of said effluent, passing said fraction through a catalytic isomerization step and thereby effecting isomerization of said butene-1 to butene-2 as substantially the sole reaction, extracting the isomerization effluent with a selective solvent having preferential solubility for butene-2 as compared to butene-1 and thereby effecting solution of the butene-2 and the butadiene content of the feed to the extraction step while allowing the normal butane and butene-1 content thereof to pass through undissolved, fractionally distilling the raffinate from said extraction step to segregate an overhead of butene-1 and a bottoms of normal butane and recycling said butene-1 to said isomerization step and said normal butane to said dehydrogenation step, stripping the dissolved butene-2 and butadiene from the rich solvent, fractionally distilling the stripped butadiene and butene-2 to produce an overhead of substantially pure butadiene and a bottoms of butene-2, catalytically dehydrogenating said butene-2 to butadiene in a second hydrogenation stage with the simultaneous formation of some butene-1, segregating a C₄ hydrocarbon fraction from the effluent, said fraction containing the butadiene, normal butane and butene-1 content and at least a portion of the butene-2 content of said effluent, and commingling said fraction with said isomerization effluent and extracting it and otherwise treating it therewith as above.
